UNITED STATES PATENT OFFICE.

JAMES M. HART, OF PORTLAND, OREGON.

GAME-CARDS.

1,357,166.

Specification of Letters Patent. Patented Oct. 26, 1920.

Application filed September 26, 1918. Serial No. 255,796.

To all whom it may concern:

Be it known that I, JAMES M. HART, a citizen of the United States, residing at Portland, in the county of Multnomah and 5 State of Oregon, have invented certain new and useful Improvements in Game-Cards; and I do declare the following to be a full, clear, and exact description of the invention, such as will enable others skilled in 10 the art to which it appertains to make and use the same.

This invention relates to card games, and it relates more particularly to certain improvements in and enlargements upon the 15 well known playing cards which comprise suits of thirteen cards each.

The main object of this invention is to provide a card game that is intimately identified with the present great war, so that 20 it will be interesting to people of all nations.

A further object is to provide a game of this character which is instructive as well as interesting and entertaining.

25 Another object is to provide a game of this character which is especially entertaining to soldiers and sailors and will contribute to their mental welfare in the intervals between engagements with the 30 enemy.

Other objects and advantages may become apparent to persons who read the following details of description in connection with the accompanying drawings in which:

35 Each of the Figures 1 to 6 inclusive is a perspective view of one of the six suits, the highest card of each suit being shown in full, only the edges of the other cards being visible;

40 Each of Figs. 7 to 12 inclusive illustrates the next to the highest of its suit;

Each of the Figs. 13 to 18 inclusive illustrates the third highest card of its suit;

Each of Figs. 19 to 24 inclusive illustrates the fourth highest card of its suit; and 45 Fig. 25 illustrates the joker.

Referring to these drawings, in which similar reference characters correspond with similar parts throughout the several views, it will be seen that the numeral 1 represents a star, 2 a heart, 3 a club, 4 a diamond, 5 a spade, and 6 a cross, the latter being in imitation of an "iron cross" 50 or German emblem. It will be noted that each suit is identified by one or more stars, hearts, clubs, diamonds, spades or crosses. The stars are intended to identify the suit which contains them with the United States of America; the hearts, to identify their 60 suit with the French Republic; the clubs, to identify their suit with Great Britain; the diamonds, to identify their suit with Belgium; the spades, to identify their suit with Italy; and the iron crosses 6, to identify their suit with the Central Powers of which Germany is considered the leader.

Moreover, each of the cards of a suit is identified with that suit and with the country, nation or belligerent it represents, by 70 abbreviations or initials such as U. S., for United States; F, for France; G. B., for Great Britain; B, for Belgium; I, for Italy; and C. P., for Central Powers. These alphabetical characters of identification 75 may be placed, as shown, in the upper left-hand and lower right-hand corners, or they may be placed otherwise if found desirable. Moreover, the highest cards may be identified with the several countries or 80 nations by the application of names or words of identification as shown in Figs. 1 to 6 inclusive.

Referring now to the second highest cards of the several suits, the reference character 85 7 designates an imitation or picture of the President of the United States; 8, a similar representation of the President of France; 9, a similar representation of the King of Great Britain; 10, a similar representation 90 of the King of Belgium; 11, the King of Italy; and 12 the Kaiser or Emperor of Germany, and leader of the Central Powers. The same or similar alphabetical characters may be employed for identifying the 95 lower cards of each suit as those which are employed for identifying the highest cards of the suit.

Referring to the third highest cards of the several suits, the reference character 100 13 is an imitation or picture of the fictitious person or character Columbia; 14, the historical character Joan of Arc; 15 the fictitious person or British character Britannia; 16, the character St. Gudula, the 105 Patron Saint of Belgium; 17, the historical character Cornelia; 18, the historical character Lucretia Borgia, who is identified with Germany by her cruelty in poisoning a large number of people.

Referring to the fourth highest card of the several suits, the reference character 19 designates an imitation or picture of the general in command of the American Armies; 20, the general of the French Armies; 21, the general of the British Armies; 22, the general of the Belgian Armies; 23, the general of the Italian Armies; and 24, the general of the German Armies, or of the Central Powers.

Referring now to the joker, the reference 10 character 25 designates an imitation or picture of a person of high military rank, and preferably a person who is identified with all of the allied nations, as generalissimo, 1 to 5 inclusive. In the present instance, we 15 personify or represent General Foch as the central figure of the joker. The arbitrary characters such as stars and hearts, diamonds, etc., are eliminated from the joker, and this card is identified as a joker by placing 20 the word "joker" above and below or to the right and left of the central picture.

In the foregoing, the description has been confined to the four highest cards of each 25 suit, and the remaining cards of the six suits will now be described, though not in specific detail, because of their similarity to the lower cards 2 to 10 of an ordinary well known deck of playing cards. In this connection, it should be understood that the 30 suits which comprise hearts, diamonds, clubs, and spades are identical with those of the ordinary playing cards, with the exception of the alphabetical characters which identify them with the countries 35 France, Belgium, Great Britain, and Italy, but in addition to these four suits, the suits which are identified with the United States and with the Central Powers are provided, the lower cards of the U. S. suit bearing 40 stars 2 to 10 respectively; and the lower cards of the Central Powers suit bearing crosses 2 to 10 respectively.

It will be seen, therefore, that each of the 45 U. S. suits consists of thirteen cards which are identified with the United States by means of the stars and also by means of alphabetical and personal characters; the French suit consisting of thirteen cards each identified with France by hearts, alphabetical characters and French characters; and each of the other suits consisting of 50 thirteen cards which are similarly identified by their respective arbitrary characters, alphabetical characters and personal 55 characters.

These game cards are applicable for playing games according to the rules of Hoyle, and such rules may be modified in various ways, so as to play war games in accordance 60 with the various phases of war or imitations or desires of the players.

It is obvious that this improved and enlarged deck of playing cards is applicable for playing games which are intimately 65 identified with the present war between the Allies and Central Powers; but my invention is not limited to the exact details which have been described in the foregoing, for the inventive idea is applicable to game cards which may be identified with any opposing parties, factions, societies or belligerents, whether between States, provinces, nations or alliances. Therefore, I am entitled to make changes within the scope of the inventive idea expressed in the foregoing description and following claims.

I claim:

1. In a deck of game cards, a suit representing a military organization of one nation and in which one card bears a picture 80 of a superior military officer, another card of this suit bearing a picture of a subordinate military officer, and a suit representing an opposing military organization of another nation in which one of the cards bears 85 a picture of a superior military officer, another card of this opposing suit bearing a picture of a subordinate military officer.

2. The combination with the spot-cards of an ordinary four-suit deck of playing 90 cards including hearts, diamonds, clubs and spades, of a fifth suit including ten cards having thereon stars from one to ten respectively, a sixth suit including ten cards having thereon crosses from one to ten respectively, cards representing historic commanding officers of different rank replacing the kings and queens of the ordinary deck, and cards representing historic commanding officers of different rank supplementing 100 the cards of said fifth and sixth suits.

3. In a deck of game cards, a suit representing a nation, and a plurality of suits representing nations and being allied for the purpose of defeating the first said suit, 105 each of said suits including a card bearing a picture of a historic military officer of the nation it represents.

4. In a deck of game cards, a plurality of suits representing opposing nations, each 110 of said suits including a card bearing a symbolic impersonation of its nation.

5. In a deck of game cards, a plurality of allied suits each representing a nation and including a card bearing a symbolic impersonation of its nation, and an opposing suit representing another nation and including a card bearing a symbolic impersonation of 115 its nation.

6. In a deck of game cards, a suit comprising spot-cards and face cards, the spots of the spot-cards being representations of the German iron cross, the face cards including pictures of the German Kaiser, a German officer subordinate to the Kaiser, 125 and an impersonation of the German nation respectively, and an opposing suit comprising spot-cards and face cards, the spot cards of said opposing nation having thereon pentacles or stars to symbolize the American 130

Nation or United States of America, the face-cards of said opposing nation bearing picture representations of the U. S. President, an American officer subordinate to 5 said President, and the impersonation of Columbia.

7. In a deck of game cards, a suit comprising spot-cards and face cards, the spots of the spot-cards being representations of 10 the German iron cross, the face cards including pictures of the German Kaiser, a German officer subordinate to the Kaiser, and an impersonation of the German nation respectively; an opposing suit comprising 15 spot cards and face cards, the spot cards of said opposing nation having thereon pentacles or stars to symbolize the American Nation or United States of America, the face cards of said opposing nation bearing picture representations of the U. S. President, an American officer subordinate to 20 said President, and the impersonation of Columbia; and a suit allied with the said opposing suit for the purpose of defeating the first said suit. 25

In testimony whereof I have hereunto set my hand in the presence of two subscribing witnesses.
